Attorney

UNITED STATES PATENT OFFICE.

CHESTER E. CARPENTER, OF ABERDEEN, SOUTH DAKOTA.

ATTACHMENT FOR HENS.

Application filed September 12, 1922. Serial No. 587,844.

To all whom it may concern:

Be it known that I, CHESTER E. CARPENTER, a citizen of the United States, residing at Aberdeen, in the county of Brown and 5 State of South Dakota, have invented certain new and useful Improvements in an Attachment for Hens, of which the following is a specification.

My invention is an attachment for hens, 10 and its principal object is to provide a device or attachment which will overcome the desire for hens to set.

A further object of the invention is to provide an attachment of this character 15 which will allow the hen to roost, but which will prevent the hen from assuming a setting position.

Another important object of the invention is to provide an attachment for preventing 20 hens from brooding which includes a pivoted poke, adapted to poke or engage the hen upon assuming a setting position, and which normally will not interfere with the hen.

25 Still another object of the invention is to provide an attachment of this character which is simple in construction, consists of few parts, and can be manufactured and sold at a minimum cost.

30 With the preceding and other objects and advantages in mind, the invention consists in the novel combination of elements, constructions and arrangement of parts and operations to be hereinafter enlarged being 35 named and illustrated in the accompanying drawings, wherein:

Fig. 1 is a side elevation of the device 40 associated with a hen's leg, the latter being shown in dot and dash lines in roosting position;

Fig. 2 is a top plan view of the device.

Fig. 3 is a longitudinal section view taken on lines 3—3 of Fig. 2.

45 Fig. 4 is a similar view showing the device in operative position;

Fig. 5 is a vertical sectional view taken on line 5—5 of Fig. 1.

Referring in detail to the drawing where- 50 in like characters of reference designate like parts throughout the several views, the numeral 5 designates a longitudinal U shaped or channel shaped member having the forward end thereof cut away to afford an abutment 6. This channel shaped member 5 55 carries a sleeve 7 adapted to embrace the leg of the hen, as shown in Fig. 1. This

sleeve 7 is formed of complementary hinged sections 8, the free ends of which are formed with curved extensions 9 which receive a 60 slideable locking plate 10 to hold the sleeve in position on the hen's leg.

Pivoted between the rear ends of the channel shaped or U shaped member 5 is an inverted U shaped member 11 from the opposite sides of which divergent sleeves 12 extend, adapted to receive the outside toes of 65 the hen. An extension 13 is pivoted in the outer end of the inverted U shaped member 11 and carries a sleeve 14 which receives the intermediate toe of the hen. 70

Pivoted to the U shaped member 5 adjacent the pivoted end of the member 11 is a U shaped poke 15 which has its free end formed with laterally extending wings 17. Normally this poke 15 is received in the 75 channel shaped or U shaped member 5 as shown in Figs. 1 to 3 inclusive. Pivottally connected with the free end of the extension 13 and the lower edge of the poke 15 is a link or rod 16. 80

With the device in position on the hen as shown in Fig. 1 it will be seen that the hen can manipulate her toes without operating the poke 15; however, when the hen attempts to assume a setting position the 85 intermediate toe assuming a horizontal position will swing the sleeve 14 forwardly, thus moving the link or rod 16 forwardly and swinging the poke 15 to a vertical position to engage or poke the hen's breast. 90

I have entered into a somewhat detailed description of the present and preferred embodiment in order to impart a definite understanding of the same. I do not desire, however, to be understood as restricting myself to the exact construction shown and described, as various changes or modifications may be made in the form, size, and minor details of construction without departing from the principles or sacrificing any of 95 the advantages of this invention.

Having thus described my invention, what I claim, and desire to secure by Letters Patent, is:

1. An attachment for hens including a 105 member to be received on one leg of the hen, a poke pivoted thereto and normally disposed in a position parallel to the member, and means operated by the hen's toes upon assuming a setting position to swing the 110 poke at right angles to the member.
2. A device of the character described.

including a sleeve to be received on one of the hen's legs, a poke pivoted thereto and normally disposed parallel to the sleeve, and means actuated by the hen's toes upon assuming a setting position to swing the poke at right angles to the sleeve to engage the hen.

3. A device of the character described comprising a sleeve to be received on the 10 hen's leg, a channel shaped member normally received therein, and means connected with the poke and adapted to be actuated by the hen's toes upon assuming a setting position to swing the poke into engagement 15 with the hen.

4. A device of the character described comprising a sleeve to be received on one of the hen's legs, a channel shaped member carried thereby, a pivoted poke carried by the 20 channel shaped member, a member pivoted to the channel shaped member, a toe engag-

ing member pivoted to the pivoted member, and an operative connection between the toe engaging member and the poke whereby to swing the latter into engagement with the 25 hen upon actuation of the toe engaging member.

5. A device of the character described comprising a tubular member to be received on one leg of the hen, a channel shaped member carried thereby, a second channel shaped member pivoted to the first mentioned channel shaped member, divergent toe receiving members extending from the last mentioned channel shaped member, a movable toe engaging member carried by the last mentioned channel shaped member, a poke pivoted within the first mentioned channel shaped member, and link pivotally connected with the poke and movable toe actuated 35 member.

CHESTER E. CARPENTER.
